UNITED STATES PATENT OFFICE

2,075,323

RADIATOR CABINET

Clarence M. Woolley, New York, N. Y., assignor
to American Radiator Company, New York,
N. Y., a corporation of New Jersey

Application October 30, 1935, Serial No. 47,364

4 Claims. (Cl. 257—137)

My invention relates to heating cabinets, and more particularly to heating cabinets in which provision is made for forced circulation of air over a thermal radiator.

6 Embodiments of my invention include a casing adapted to substantially enclose an ordinary thermal radiator, suitable air ingress and egress openings in the casing, and air-circulating means positioned in the upper part of the casing above 10 the thermal radiator.

A preferred form of the present invention comprises a casing supporting in its upper part one or more motor-fan assemblies, an adjustable septum provided with an opening or openings 15 correlated respectively with the fan or fans of the motor-fan assemblies, air ingress, or egress openings communicating with the interior of the casing above the septum, and air egress or ingress openings communicating with the interior of 20 the casing at a point below the septum and lowerly of a thermal radiator over which the casing as a whole is adapted to fit and to substantially enclose.

During the operation of the motor-fans in 25 this preferred construction, the septum being adjusted to a closed position in substantial alignment with the mean path of rotation of the fans proper, air is projected downwardly over the heat transferring surfaces of the radiator and 30 is discharged at a predetermined point near the floor of the room or other space served by the radiator over which the heating cabinet is placed, thereby positively heating a maximum volume of the room air, and also most effectively distributing 35 heat uniformly throughout the room.

When the fans are not in operation, assuming steam or like heating medium to be supplied to the radiator, by setting the septum at an angle inclined upwardly toward the openings in the 40 upper portion of the casing, an air channel is formed which directs gravity or convection currents flowing upwardly through the heating cabinet toward and through said openings.

45 Further features of the invention will be more fully understood from the following detail description and accompanying drawing in which:

Fig. 1 is a front elevation of a preferred embodiment of my invention, a portion of the front 50 panel being broken away to reveal a partial vertical section taken on line 1—1 of Fig. 2.

Fig. 2 is a side elevation of the embodiment of 55 my invention illustrated in Fig. 1, portions of the side panel being broken away to reveal a partial section taken on the line 2—2 of Fig. 1.

Referring to the drawing, the numeral 10 indicates a casing formed preferably of a single sheet of metal shaped to provide, integrally related, the front panel 11, the end panels 12 and 13, and the partial rear panel 14, and adapted 5 to fit over and substantially enclose a heating radiator 15 which may be a part of an ordinary type of heating system, supplied with a suitable heating medium such as steam. Inwardly angled, integral extensions 10a at the bases of the 10 aforesaid panels may serve as feet for the support of casing 10 on the floor 16 of a room or other space served by my heating cabinet. Preferably, both the thermal radiator and the casing are supported on the floor independently of each 15 other.

A cover 17 is provided to tightly close the top of the casing while in use, and desirably its construction permits convenient access to mechanism enclosed within the casing. As illustrated, 20 it may be of a removable slide-fit type locking frictionally with the side panels of the casing by means of peripheral channelled drop-flanges 17a, and adapted to bear tightly against angled supporting members 10b formed as extensions 25 of the upper part of the casing.

In the upper portion of the casing and above the thermal radiator I provide air circulating means. As such, one or more motor-fan assemblies 30 may be utilized. The illustrated embodiment shows three such assemblies, each motor being indicated 18 and its associated fan 19. Each motor-fan assembly is suitably supported by the casing, as by means of the suspension cross bar 20, which is cushioningly supported in channel depressions 21a and 22a respectively of the brackets 21 and 22, said brackets being firmly secured to the interior face of the front and rear panels of the casing by welding, riveting, or the like, and being suitably spaced apart from each 40 other as required by the length of the suspension cross-bar 20.

Cushioning means, in the form of rubber sleeves 45 23 or the like, fitted over each end of the suspension cross-bar 20 serve to absorb operating vibrations from the motors 18; the motors are suspended, as by means of the suspension clamps 24, from advantageous points along the suspension cross-bar.

The suspension clamps 24 as shown are preferably formed from resilient strap metal. They comprise inverted U suspension members 24a, rigidly fastened as by riveting, to the cross-bar 20; and annular clamping members 24b, of the common bolt-nut adjustable type, rigidly at- 50 55

tached, as by welding, to the terminals of the inverted U suspension member 24a.

Coordinating with the fan or fans 19 is provided a septum 25, extending entirely across the horizontal sectional area of the casing and including one or more, depending on the number of fans, fan openings 25a. The septum 25 is preferably adjustably mounted as by hinges 25b, to a suitable interior face of the casing, in this instance the interior face of the rear panel 14. Each of the fan openings 25a has a diameter slightly larger than the effective diameter of the therewith coordinated fan.

Ingress, or egress as the case may be, openings for air are shown in the illustrated preferred embodiment at 26, in this instance being disposed wholly in the front panel 11 of the casing 10 and located above the septum 25. The openings are here shown in the form of an ornamental grill extending across the upper part of the front. However, the openings are not restricted in location to the front panel. If desired they may be suitably positioned in other panels of the casing, provided they are above the septum 25. Air egress or ingress openings, indicated 27, are supplied at the bottom of the casing, communicating with the interior of same at a point below the septum 25, and below the effective heating surface of the radiator 15.

In the preferred embodiment illustrated, upon actuation of the one or more motors 18, which motors are desirably of the electric type controlled by a snap switch 28, and therewith actuation of the one or more fans 19, air is drawn in to the cabinet through the openings 26, serving at this stage as air ingress openings, and is thereupon projected downwardly within the cabinet through the respective fan openings 25a of the septum 25 in heat exchange relation with the heating surfaces of the radiator 15, and is finally forced outwardly of the cabinet through the opening or openings 27, serving at this stage as air egress openings, at or in immediate proximity to the floor 16. In this manner my heating cabinet is operative to positively circulate and recirculate heated air within the room or other space in which it is placed with attendant enhanced comfort to the occupants of the said room or other space, by reason of such positive circulation and the resulting uniform distribution of heat supplied by the radiator.

When forced air circulation through the cabinet is not desired, the motors 18 are discontinued in operation, at which stage it is desirable to raise the septum 25 about its hinges 25b from its horizontal position shown in Fig. 1 to an angular position indicated in dotted outline at 25' in Fig. 2. Such adjustment is accomplished by any suitable means, such as the angular supporting piece 29 which may be slidably mounted in the slot 30, which slot may be suitably formed in the end panel 12. The supporting piece 29 may be adjusted to a desired elevated position, thereby effecting a corresponding adjustment of the septum 25, by manually sliding it upwardly in the slot 30, and then may be frictionally locked in the set position by the screw-clamp handle member 31. The septum 25 may be lowered and/or returned to its horizontal position by corresponding setting and locking of the member 29.

When the septum is elevated it serves to form a channel with the side panels of the cabinet to direct gravity i. e., convection air currents flowing upwardly through the heating cabinet, and such channel cooperates with the openings 26

which now serve as air egress openings. Volumetric delivery of heated air through the openings 26 is thus controlled by variable adjustment of the supporting piece 29, and consequent adjusted setting of the septum 25.

At opposite lateral ends of the front panel 11 as illustrated, or at any other convenient location in the casing 10, may be provided utility doors 30, preferably of an ornamental design and so positioned as to afford access to supplied fittings such as the conventional shut-off valve 15a and the steam trap 15b, indicated in dotted lines in Fig. 1, of the radiator 15. Such doors may be removably secured in position by means of one or more hook members 30a, adapted to fit over a strap portion 11a which may be an integral part of the front panel 11, and may be manipulated by means of the knob or handle 30b.

The electric switch 28 may provide for multiple speed actuation of the fan or fans or equivalent; advantageously, such current controlling switch may be thermostatically responsive, most advantageously responsive thermostatically to differential temperature setting, as for example, providing for full speed of each motor-fan assembly 25 for a set minimum temperature, half or other partial speed for a set intermediate temperature, and "off" for a set maximum temperature.

I claim:

1. A heating cabinet including in combination a casing adapted to substantially enclose a heating element, one or more motor-fan assemblies housed in the casing above said heating element, means supporting said one or more motor and fan assemblies and wholly supported by said casing, a displaceable septum provided with an opening or openings correlated with the fan or fans of such motor and fan assembly, said casing being provided with openings communicating with the interior of the casing above said septum, said casing being further provided with an opening or openings communicating with the interior of the casing below said heating element.

2. A heating cabinet including in combination a casing adapted to substantially enclose a heating element, one or more motor-fan assemblies housed in the casing above said heating element, means supporting said one or more motor and fan assemblies and wholly supported by said casing, an upwardly tiltable septum provided with an opening or openings correlated with the fan or fans of such motor and fan assembly, said casing being provided with openings communicating with the interior of the casing above said septum, said casing being further provided with an opening or openings communicating with the interior of the casing below said heating element.

3. A heating cabinet including in combination a casing adapted to substantially enclose a heating element, one or more motor-fan assemblies housed in the casing above said heating element, means supporting said one or more motor and fan assemblies and wholly supported by said casing, an adjustably displaceable septum provided with an opening or openings correlated with the fan or fans of such motor and fan assembly, and means for retaining said displaceable septum in adjusted status said casing being provided with an opening or openings communicating with the interior of the casing above said septum, said casing being further provided with an opening or openings communicating with the interior of the casing below said heating element, said displaceable septum being mounted for displacement, correlated with the first mentioned opening or open-

ings, for directing air currents through said opening or openings.

4. A heating cabinet including in combination a casing adapted to substantially enclose a heating element, one or more motor-fan assemblies housed in the casing above said heating element, means supporting said one or more motor and fan assemblies and wholly supported by said casing an adjustably upwardly tilttable septum provided 10 with an opening or openings correlated with the fan or fans of such motor and fan assembly, and

means for retaining said displaceable septum in adjusted status, said casing being provided with an opening or openings communicating with the interior of the casing above said septum, said casing being further provided with an opening or 5 openings communicating with the interior of the casing below said heating element, said upwardly tilttable septum being pivoted to swing in an arc transverse of the area of the first mentioned opening or openings.

CLARENCE M. WOOLLEY.
